UNITED STATES PATENT OFFICE.

HARRY J. THOMAS, OF GREENSBORO, NORTH CAROLINA.

CAR RERAILER.

Application filed April 7, 1923. Serial No. 630,438.

To all whom it may concern:

Be it known that I, HARRY J. THOMAS, a citizen of the United States, residing at Greensboro, in the county of Guilford and State of North Carolina, have invented certain new and useful Improvements in Car Rerailers, of which the following is a specification.

My invention relates to an improvement 10 in car rerailers, and has for its primary object to substantially improve upon similar devices now universally employed for the rerailing of cars.

A further object of this invention is the 15 provision of such a rerailer that may be expeditiously positioned upon the rail at opposite sides thereof, and wherein the tendency of the same to slip upon the rail is reduced to a minimum.

20 A further object of this invention is the provision of such a device, that will embrace the desired features of simplicity, durability and efficiency, and that may be manufactured and marketed at small cost.

25 The nature and advantages of the invention will be better understood when the following detailed description is read in connection with the accompanying drawings, the invention residing in the construction, 30 combination, and arrangement of parts as claimed.

In the drawings forming part of this application, like numerals of reference indicate similar parts in the several views, and 35 wherein:—

Figure 1 is a top plan view of my rerailer applied.

Figure 2 is an elevation of the inner side thereof.

40 Figure 3 is an end elevation of the device, and

Figure 4 is a cross section taken substantially upon the line 4—4 of Figure 1.

45 This rerailer comprises a relatively elongated rectangular shaped casting, of a length sufficient to engage upon at its opposite ends a pair of ties designated *a*. This casting has a flange 5 at its outer side and ends which is formed upon its under surface 50 near its outer longitudinal edge and end edges with prongs or spikes 6, which extend inwardly towards the center of the device, and are adapted to be forced into the said ties for effectively over-coming any tendency of the rerailer to creep.

55 This casting is formed with an upwardly

extending bulged member or raised portion 7, the outer side thereof extending substantially parallel with the adjacent edge of the flange 5, and being inclined and curved slightly inwardly towards the apex of the member 7.

The opposite ends of the said portion 7 are curved inwardly as more clearly shown in Figure 1, these ends being also rounded as more clearly shown in Figure 2, whereby the car wheels are raised upwardly above the surface of the rail designated *b*. The bulged member 7 is formed with a wing-shaped, flattened upper portion 7¹, which is longitudinally inclined from the center of said member outwardly toward its opposite ends and laterally toward the rail, the ends of said flattened top portion diverging from the center of said member away from the rail.

Formed upon the inner edge of the said raised or bulged portion 7, and at a distance above the flange 5, equivalent to the height of the said rail *b* is an inwardly extending flange portion 8, that engages over the said rail, in a manner clearly shown in several of the views.

The top surface of this flange 8 is longitudinally, upwardly curved or of arcuate shape, the ends thereof being in close engagement with the rail when the device is in use for permitting of the easy engagement of the car wheels thereon. Between this flange 8, and the said raised or bulged portion is a longitudinal car wheel flange groove 9, while the outer edge of said flange 8 is formed with a pendent skirt portion 10, the upper side thereof being shouldered at 11, also effecting a groove for the flanges of said car wheels, when the device is employed upon the opposite rail.

In view of the above description, it will at once be apparent that when my rerailer is positioned as shown in the drawings, and when the car is moved forwardly, the wheels thereof will engage upon the said bulged or raised portion 7, whereby a continued movement of the car will force these wheels upwardly, the flanges of the wheels upon one side of the car engaging within the innermost groove 9, the wheel treads running upon the flange 8, whereby through a still further movement of the car beyond the rerailer, the wheels will be brought into the position upon the rails.

Although I have herein shown and de-

scribed the preferred embodiment of the present invention, it is nevertheless to be understood that minor changes may be made therein, without departing from the spirit and scope of the invention as claimed.

Having thus described my invention, what I claim as new, and desire to secure by Letters Patent, is:

In a car rerailer, a casting embodying an upwardly bulged hollow member open at its bottom and formed with its outer side and ends curving inwardly and upwardly toward the rail and above the latter, said member being further formed with a wing-shaped flattened upper portion inclined longitudinally from the center of said member downwardly toward its opposite ends and laterally toward the rail, the ends of said flattened top portion diverging from

the center of said member away from the rail, an outwardly directed flange upon the lower edges of the ends and outer side of said member provided with dependent tie-engaging prongs, a laterally extending flange having a longitudinal upwardly curved upper surface and formed upon the lower inner side of said bulged member and adapted for positioning upon the rail, said member being formed with a longitudinal extending groove at the inner side of said flange, and a pendent skirt formed upon the outer longitudinal edge of said flange with its upper edge terminating below the upper surface of said lateral flange for providing a shoulder, substantially as shown and for the purpose described.

In testimony whereof I affix my signature.

HARRY J. THOMAS.
